Primary Examiner — Natasha Vujcic*Assistant Examiner* — Gilbert B Ford(74) *Attorney, Agent, or Firm* — Schwegman Lundberg & Woessner, P.A.(57) **CLAIM**

The ornamental design for a breast pump valve, as shown and described.

DESCRIPTION

FIG. 1 is a top perspective view of a breast pump valve showing my new design;

FIG. 2 is a bottom perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof, the left side view being a mirror image of FIG. 7;

FIG. 8 is an exploded top perspective view thereof; and,

FIG. 9 is an exploded bottom perspective view thereof.

1 Claim, 9 Drawing Sheets
